(57) **ABSTRACT**

A new distinct variety of grapevine named ARDTHIRTYEIGHT abundantly forms attractive crunchy seedless elongated berries with a yellow-green skin coloration, medium density and medium sized clusters which display a naturally sweet flavor which is ready for harvesting during August in San Joaquin Valley of Central California, U.S.A, and displays good eating qualities as a table grape, having a firmness amenable for handling, shipping, and storage.

1 Drawing Sheet

2

It was found that the new grapevine of the present invention possesses the following combination of characteristics:

- (a) Forms attractive crunchy seedless elongated berries with a yellow-green skin coloration; in medium density and medium sized clusters which display a naturally sweet flavor,
5 (b) Commonly bears fruit during the month of August in the San Joaquin Valley of Central California, U.S.A., and
(c) Bears fruit that is firm and is well amenable for storage, handling, and shipping.
(d) Produces 40 bunches per vine, and an average of about 1-2 bunches per shoot, at a total of 48 lbs. fruit per vine.
10 (e) The new variety during observation to date has displayed no visible disease, and has displayed an ability to well resist cold, drought, heat; but sensitive to direct exposure to sun and wind. The fruit of the new variety has been found to display excellent handling and shipping qualities combined with desirable dessert eating qualities.
15 (f) The new variety of the present invention has been found to undergo asexual propagation beginning in 2012 near Bakersfield in the San Joaquin Valley of Central California, U.S.A. by bud grafting on mature Thompson rootstock
20 (g) (non-patented in the United States). Such asexual propagation has been conducted thereafter in successive years to date and has shown that the characteristics of the new variety are strictly transmissible from one generation to another. Accordingly, the new variety undergoes asexual propagation
25 in a true to type manner.

The new variety of the present invention has been found to undergo asexual propagation beginning in 2012 near Bakersfield in the San Joaquin Valley of Central California, U.S.A. by bud grafting on mature Thompson rootstock (non-patented in the United States). Such asexual propagation has been conducted thereafter in successive years to date and has shown that the characteristics of the new variety are strictly transmissible from one generation to another. Accordingly, the new variety undergoes asexual propagation in a true to type manner.

SUMMARY OF THE INVENTION

The new variety ARDTHIRTYEIGHT is a white seedless table grape with a high production, e.g., about 40 bunches per vine, and an average of about 1-2 bunches per shoot.

TABLE 1

ARDTHIRTYEIGHT compared with parent & closely related variety:			
Variety/ Characteristic	ARDTHIRTY- EIGHT	ARRA- FIFTEEN	AUTUMN KING
Skin	Medium	Thin	Medium
Berry shape	Crunchy	Crispy, Meaty and Juicy	Meaty & Soft
Berry size	21 mm x 40 mm	22 mm x 33 mm	24 mm x 29 mm

The parentage of the new variety can be summarized as follows:

ARRAFIFTEEN

The new variety of the present invention was found as a mutation during asexual propagation in 2010 near Bakersfield in the San Joaquin Valley of Central California, U.S.A. by bud grafting on mature Thompson rootstock (non-patented in the United States).

Asexual reproduction by micro propagation of the new variety as performed near Bakersfield, Calif., U.S.A., shows that the forgoing and other distinguishing characteristics come true to form and are established and transmitted through succeeding propagations.

BRIEF DESCRIPTION OF THE DRAWING

The accompanying photographic illustration shows typical six-year-old specimens of the new variety, vegetatively propagated, in color as nearly true as it is reasonably possible to make in a color illustration of this character. Colors in the photograph may differ from the color values cited in the detailed botanical description below, which accurately describes the colors of the new Grapevine.

FIG. 1 shows leaves, stems and grapes of ARDTHIRTYEIGHT.

DETAILED BOTANICAL DESCRIPTION

The chart used in the identification of colors is The RHS Colour Chart of The ROYAL HORTICULTURAL SOCIETY (3rd Edition). The description is based on the observation of plants growing on 'Thompson Seedless' rootstock outdoors near San Joaquin Valley of Central California, U.S.A.

VINE CHARACTERISTICS:

vigor	Vigorous upright shoots
productive capacity	Bearing at a natural, average capacity. Spur pruning.
trunk	Strong and developed. Diameter is 2.3 inches, measured at 9 inches above ground. Rough with a fibrous, shaggy exterior. Light maple brown coloring (greyed orange 166D)

Date of bud burst in Bakersfield, Calif.—February 26th.

YOUNG SHOOT CHARACTERISTICS:

Openness of tip	fully open
Density of prostrate hairs on tip	absent or very sparse
Anthocyanin coloration of prostrate hairs on tip	None (yellow green 149C)
Density of erect hairs on tip	absent or very sparse

YOUNG LEAF CHARACTERISTICS:

Color of upper side of blade	yellow green 144A
Color of lower side of blade	yellow green 145A
Density of erect hairs between main veins on upper side of blade	sparse
Density of erect hairs between main veins on lower side of blade	absent or very sparse
Density of prostrate hairs on main veins on upper side of blade	absent or very sparse
Density of prostrate hairs on main veins on lower side of blade	sparse

5

SHOOT CHARACTERISTICS:

Attitude (before tying)	semi-erect
Color of dorsal side of internodes	yellow green 144B
Color of ventral side of internodes	yellow green 144C
Color of dorsal side of nodes	yellow green 145A
Color of ventral side of nodes	yellow green 145B
Density of grata hairs on internodes	absent or very sparse
Density of prostrate hairs on internodes	absent or very sparse
Length of tendrils	7.5 inches
Diameter of tendrils	0.09 inches
Color of tendrils	yellow green 145A
Number of tendrils at bloom	4
Positioning of first flowering and fruiting node	the first bunch is in the 3rd node
Inflorescence number per flowering shoot	1-2

20

FLOWER CHARACTERISTICS:

Reproductive organs	fully developed stamens and fully developed gynoecium
Flower length	0.2 inches
Flower diameter	0.1 inches
Pistil length	0.08 inches
Pistil color	yellow green 144A
Pollen Amount	rich
Pollen color	yellow 11C
Stamen color	yellow green 144A
Stamen length	0.17 inches
Number of stamen	6

30

First bloom in Bakersfield, Calif.—April 27th.

Date of full bloom in Bakersfield, Calif.—May 5th.

35

MATURE LEAF CHARACTERISTICS:

Size of blade	7.5 x 6 inches
Shape of blade	wedge-shaped
Base descriptors	wedge-shaped
Leaf margin	doubly serrate
Leaf apex	acute
Blistering of upper side of blade	absent or very sparse
Depth of upper lateral sinuses	shallow
Number of lobes	five
(Only varieties with lobed leaves)	
Arrangement of lobes of upper lateral sinuses	slightly overlapped
Arrangement of lobes of petiole sinus	half open
Length of teeth	0.6 inches
Ratio length/width of teeth	medium
Shape of teeth	both sides straight
Density of prostrate hairs between main veins on lower side of blade	absent or very sparse
Density of erect hairs on main veins on lower side of blade	medium
Density of erect hairs between the main veins on upper side of blade	medium
Density of prostrate hairs on main veins on upper side of blade	absent or very sparse
Length of petiole compared to length of middle vein	moderately shorter
Top side color	yellow green 147A
Bottom side color	yellow green 147B
Texture of upper side of blade	little rough
Texture of lower side of blade	rough
Vein color on upper blade	yellow green 145B
Vein color on lower blade	yellow green 145D
Venation pattern for upper blade	netlike venation
Venation pattern for lower blade	netlike venation
Petiole length	3.9 inches

65

-continued

MATURE LEAF CHARACTERISTICS:	
Petiole diameter	0.14 inches
Petiole color	yellow green 145A
Petiole texture	smooth

*Date of beginning of berry ripening in Bakersfield
Calif.—July 16th.*

BUNCH CHARACTERISTICS:	
Size (peduncle excluded)	medium
Density of berries on bunch	medium
Bunch length	5.8 inches
Bunch diameter	4.5 inches
Length of peduncle of primary bunch	1.5 inches
Diameter of peduncle of primary bunch	0.11 inches
Peduncle of primary bunch color	yellow green 145B
Peduncle texture	smooth
Bunches per vine	40
Average bunch weight	1.2 lbs

BERRY CHARACTERISTICS:	
Size	large
Length	1.5 inches
Weight	0.3 oz
Diameter	0.7 inches
Shape	cylindrical
Color of skin (without bloom)	yellow green 150A
Flesh color	yellow green 145C
Brix	21
Titratable acidity percentage	0.7%
Juice	3.4 pH
Ease of detachment from pedicel	moderately easy
Thickness of skin	medium
Anthocyanin coloration of flesh	none
Firmness of flesh	moderately firm
Particular flavor	natural sweet
Formation of seeds	none
Berries per bunch	95

PEDICEL CHARACTERISTICS:	
Length	0.6 inches
Diameter	0.1 inches
Color	yellow green 1440
Pedicel texture	rough

WOODY SHOOT CHARACTERISTICS:	
Woody shoot texture	rough
Woody shoot color	greyed orange 165B
Woody shoot length	72 inches
Diameter	0.4 inches
Internode length	4.2 inches

Market use of observed plants.—Fresh market.

- 10 Age and growing conditions: Six years growing under Y system in South Joaquin Valley (hot, dry summers).
Shipping characteristics: Number of days fruit has been stored under specific conditions: Fruit was in cold storage. Stored in poly bags inside Styrofoam boxes with sulfur pads. After 30 Days: rachises were 60% green; 3% berry shattering; no berry wrinkling or cracks were apparent.
15 DNA profile: To further characterize the new variety DNA was extracted from plant samples and a DNA profile was obtained at California Seed & Plant Lab, California USA using base pairs for 10 standard microsatellite DNA markers. The data is presented hereafter.
20

TABLE 2

DNA profile for ARDTHIRTYEIGHT		
Microsatellite DNA Marker	Allele Sizes in Base Pairs	
M1	228	238
M2	249	249
M3	179	194
M4	216	220
M5	273	273
M6	145	151
M7	187	205
M8	247	255
M9	214	214
M10	237	247

The ARDTHIRTYEIGHT variety has not been observed under all possible environmental conditions to date. Accordingly, it is possible that the phenotypic expression may vary somewhat with changes in light intensity and duration, cultural practices, and other environmental conditions.

Additional information relating to plant and fruit disease and pest resistance or susceptibility has not been observed to date. Specification of the plant hardiness zone and the heat/cold resistance has not been observed to date.

What is claimed is:

1. A new and distinct grapevine, botanically known as *Vitis vinifera*, identified as ARDTHIRTYEIGHT, substantially as shown and described herein.
